WINDING MACHINE

John O. McKean, Westfield, Mass., assignor to
 Foster Machine Company, Westfield, Mass., a
 corporation of Massachusetts

Application February 13, 1933, Serial No. 656,455

6 Claims. (Cl. 242—43)

One object of my invention is to provide certain improvements in the construction, form and arrangement of a lifting thread bar for winding machines, in which the winding of the package is begun previous to the leading of the thread into the thread traversing means.

Another object of my invention is the provision of a lifting thread bar pivotally mounted upon the stop motion cover in such a manner as to effect the previous named object.

Another object of my invention is to provide a means whereby whipping and cutting of the thread by the thread traversing means previous to the attainment of full speed by the rotating package is obviated by holding the thread out of the thread guide until the full speed of the package is attained.

Other objects and advantages will be apparent as my invention is further described.

20 A practical embodiment of my invention is represented in the accompanying drawings, in which

Fig. 1 represents a vertical transverse section through so much of a winding machine as will give a clear understanding of my improved lifting 25 thread bar, the parts being in the positions they assume when the yarn has broken or become exhausted and the package has been lifted away from its winding roll.

Fig. 2 represents a vertical transverse section 30 through the same portion of the winding machine, the parts being in the positions they assume when the hand lever has been fully depressed for temporarily depressing and holding the detector wire, for lifting the package controlling rack bar out of 35 engagement with its lever arm and for temporarily raising the lifting thread bar to hold the thread out of the thread guide.

Fig. 3 represents a view similar to Figs. 1 and 2 with the parts in the positions they assume under 40 normal running conditions.

Fig. 4 represents the stop motion cover and lifting thread bar in front elevation, and

Fig. 5 represents an end view of the same.

It should be understood that by the term 45 "thread" as used in this application, I mean to include yarn, cord or other media which can be successfully handled by the machine.

The winding roll 1 revolves the package 2 by frictional surface contact therewith, the package 50 in the present instance being shown as a cop. The package is carried by a forwardly projecting arm 3 of a rock lever mounted on a shaft 4, the depending arm 5 of this rock lever having pivoted thereto at 6 the rear end of a rack bar 7. The 55 ratchet toothed portion 8 of the rack bar normally

engages a tooth 9 on the depending arm 10 of a rock lever loosely mounted on a pivot pin 11, which lever has an uprising arm 12 to which one end of a coil spring 13 is attached for yieldingly holding the depending arm 10 at the limit of its rearward movement with its stop 14 in engagement with a frame bar 15. The coil spring 16 connects the depending lever arm 5 with the rack bar 7 so as to ensure the engagement of the toothed portion 8 of the rack bar with the tooth 9 of the depending loose lever arm 10.

The traverse guide 17 for the yarn is reciprocated in the usual manner by a cam surface 18 fast on the cam shaft 19. This cam shaft 19 also carries a kicker cam 20, preferably provided with a single lobe, which cam serves as a part of the tripping mechanism for the stop motion mechanism.

The detector wire 21 of the tripping mechanism is normally held depressed by the yarn as it passes to the package during the winding thereof. This detector wire is carried by a rock lever 22 which swings on a pivot pin 23 carried by the latch lever 24 of the tripping mechanism, this latch lever in turn swinging on a pivot pin 25. A tripping roller 26 is carried by the detector lever 22. Metal to metal contact between the kicker cam and tripping roller is obviated in this construction by making the roller of some suitable non-metallic material, such for instance as hard fibre. This tripping roller is normally held out of the path of the kicker cam by the depression of the detector wire 21 due to its contact with the yarn as it passes to the package. Should the yarn break or become exhausted, the tripping roller 26 is automatically swung into the path of and into rolling contact with the kicker cam 20 the moment the detector wire 21 is permitted to rise.

The end of the spring 13 opposite to that which is attached to the uprising arm 12 of the rack engaging lever is attached to the latch lever 24 for normally holding the latch lever in its operative position in engagement with the hand lever.

The three-armed hand lever 27, 28, 29 swings on the pivot pin 11. A spring 30 is attached at one end to the uprising arm 28 of the hand lever and at its other end to the frame for swinging the hand lever to its raised position when it is released by the latch lever 24 of the tripping mechanism. The forwardly projecting arm 27 of the hand lever is provided with an extension 31 which is developed into a handle 32 for depressing the lever. The rearwardly projecting arm 29 of the hand lever is provided with a hook pin 33 arranged to raise the ratchet toothed portion 8 of the rack 55

bar out of engagement with the tooth 9 of the depending lever arm 10 at or near the end of the depression of the hand lever, after fulcrum projection 364, to be presently described, has raised lifting thread bar 36, also to be presently described. This relation of the parts is shown in Fig. 2.

10 The stop motion cover 34 swings on a pivot pin 35 carried by the forwardly projecting arm 27 of the hand lever, which pin 35 also coacts with the latch lever 24 to cause the latch lever to hold the hand lever in its nearly depressed position, as shown in Fig. 3, when the package is being wound. A lifting thread bar 36 is carried 15 by a lifting thread bar holder 361 which is pivoted by pivot pins 362 to the stop motion cover 34. This lifting thread bar extends in close proximity to the traverse guide 17 and is attached to the lifting thread bar holder 361 by means of lugs 363. 20 Lifting thread bar holder 361 is so shaped as to rest proximate to fulcrum projection 364 when the stop motion mechanism is in its running position, as shown in Fig. 3. Lifting thread bar holder 361 is provided with a projecting stop 365 which serves to limit its downward pivotal motion when the parts are in a knock-off position as shown in Fig. 1, permitting lifting thread bar holder 361 to be lifted away from the fulcrum projection 364. A screw 37 carried by the cover 25 34 and slidably engaged with the frame is used for adjusting the position of the cover, a spring 38 serving yieldingly to hold the cover in its adjusted position.

30 The bobbin from which the yarn is fed is denoted by 39 and the threaded yarn by 40. The tension device through which the yarn is passed is denoted by 41.

35 The one-way interlocking connection between the hand lever and latch bar controlling lever is shown as comprising an offset lug 42 on the depending lever arm 10 arranged in position to be engaged by a depending lug 43 on the hand lever.

Operation

40 45 To start the winding of the package, the hand lever is fully depressed into the position shown in Fig. 2, thereby swinging down the detector wire below the path 40 of the yarn. This depression of the hand lever lowers stop motion cover 34 to its lowest position, rocks the parts 361, 363 and 36 upon the fulcrum projection 364, and thus keeps the yarn 40 high enough above the thread guide 17 so that when the full depression 50 of the hand lever causes the hook pin 33 to raise the rack bar 7 out of engagement with the lever arm 10, thereby permitting the package 2 to drop down onto the winding roll 1, nevertheless the thread is kept away from the thread guide until the return of the handle to running position. 55 60 The spring 13 is permitted to swing the lever arm to the limit of its rearward movement.

65 70 As soon as the yarn starts winding, the hand lever is released and it will immediately rise slightly to the position shown in Fig. 3 where its pin 35 will be engaged by the latch lever 24 re-leasably locking the hand lever in position. This slight raising of the handle raises also the stop motion cover 34, rocks the parts 361, 363 and 36 upon the fulcrum projection 364, lowering the thread bar 36, permitting the yarn to drop into the traverse guide 17.

75 When the yarn breaks or becomes exhausted, the detector wire 21 will be permitted to rise to the position shown in Fig. 1, thereby causing the tripping roller 26 to be moved into the path of

5 and into rolling contact with the kicker cam 20. As the kicker cam revolves, it will throw the roller out of the path of the cam and thereby swing the latch lever forward causing it to be disengaged from the latch pin 35 on the hand lever. The spring 30 immediately raises the hand lever to the position shown in Fig. 1, thereby causing the lever arm 10, because of its one-way interlocked connection 42, 43 with the hand lever, to pull the rack bar 7 forward, lifting the package off of the winding roll 1. The spring 16 ensures the locking engagement between the rack bar 7 and the depending lever arm 10 when released from the hook pin 33, thereby maintaining the package in its raised position out of contact with the winding roll. This lifting movement of the hand lever also raises the stop motion cover 34 causes projecting stop 365 to contact with it and lifts lifting thread bar holder 361 and its integral parts away from the fulcrum projection 364.

10 15 20 25 30 35 It will thus be seen that I have devised a lifting thread bar for winding machines wherein the package begins to wind previous to the thread coming into contact with the traversing guide, thus avoiding the troublesome and expensive whipping, cutting, and weakening of the thread when the thread is caught by the thread guide while it is still stationary, or moving slowly. It will also be seen that other advantages inhere in my present construction which need not here be enumerated.

The patentable elements shown and described but not claimed herein are covered by claims of my copending application filed Dec. 6, 1930, Serial No. 500,495, now Patent No. 1,958,060, issued May 8, 1934.

40 45 It is evident that various changes may be resorted to in the construction, form and arrangement of the several parts without departing from the spirit and scope of my invention, and hence I do not intend to be limited to the particular embodiment herein shown and described, but

What I claim is:

1. In a winding machine, a package holder, means for actuating said package holder, traversing means, means for engaging and disengaging said package holder from said package holder actuating means, and means thereon adapted to 50 guide the thread to the package out of the path of said traversing means until after the winding of the package starts.

2. In a winding machine, a package holder, means for actuating said package holder, traversing means, means for engaging and disengaging said package holder from said package holder actuating means, a thread bar carried by said engaging and disengaging means adapted to support the thread away from said traversing means 60 until after the winding of the package starts.

3. In a winding machine, a package holder, means for actuating said package holder, traversing means, means for engaging and disengaging said package holder from said package holder actuating means, a thread bar pivotally connected to said engaging and disengaging means, a stationary fulcrum adapted to coact with said thread bar, said fulcrum and pivoted thread bar being adapted to support the thread away 70 from said traversing means when said engaging and disengaging means is in a position to become engaged.

4. In a winding machine, a package holder, means for actuating said package holder, traversing means, means for engaging and disengaging said package holder from said package holder actuating means, a thread bar pivotally connected to said engaging and disengaging means, a stationary fulcrum adapted to coact with said thread bar, said fulcrum and pivoted thread bar being adapted to support the thread away 75 from said traversing means when said engaging and disengaging means is in a position to become engaged.

wound including a traversing element and a manually actuatable non-traversing element mounted on said engaging and disengaging means.

5. In a winding machine, a frame, a projection thereon, a package holder, frictional means for actuating said package holder, thread tensioning means, traversing means operating between said thread tensioning means and said package holder, a thread bar interposed between said tensioning means and said traversing means, a stop motion cover, said thread bar being pivoted to said stop motion cover and being fulcrumed upon said projection so as to support the thread away from said traversing means at the time the package 15 begins to wind.

JOHN O. McKEAN.
